UNITED STATES PATENT OFFICE.

EDWARD YOUNG HASKELL, OF NEW LONDON, CONNECTICUT.

NAVIGATOR'S COURSE MARKER AND FINDER.

1,148,380.

Specification of Letters Patent.

Patented July 27, 1915.

Application filed December 26, 1914. Serial No. 879,105.

To all whom it may concern:

Be it known that I, EDWARD Y. HASKELL, a citizen of the United States, and a resident of New London, in the county of New London and State of Connecticut, have invented a new and Improved Navigator's Course Marker and Finder, of which the following is a full, clear, and exact description.

10 This invention relates to nautical instruments and has particular reference to devices used in connection with ships' binnacles to facilitate the direction or location of distant objects.

15 Among the objects of this improvement is to simplify the construction and operation of this character of instruments, whereby not only do I lessen the cost of the same, but I am able to produce an instrument of 20 the maximum simplicity of manipulation and control.

25 The foregoing and other objects of the invention will hereinafter be more fully described and claimed and illustrated in the drawings forming a part of this specification in which like characters of reference indicate corresponding parts in all the views, and in which—

30 Figure 1 is a fragmentary view of a ship's binnacle equipped with a preferred form of my invention; Fig. 2 is a sectional detail on the line 2—2 of Fig. 1; Fig. 3 is a vertical section of the main parts of my device on a plane at right angles to Fig. 2; Fig. 4 is a 35 plan view of the upper end of the quill or hollow stem; Fig. 5 is a front elevation of the same; and Fig. 6 is a sectional view on the line 6—6 of Fig. 3.

40 The several parts of this device may be made of any suitable materials, and the relative sizes and proportions, as well as the general design of the mechanism, may be varied to a considerable extent without departing from the spirit of the invention 45 hereinafter more fully described and specifically claimed.

50 Referring more particularly to the drawings the numeral 10 indicates the top or canopy of the binnacle within which is located the compass dial 11 in any usual or preferred manner, the same *per se* constituting no part of this invention.

At 12 I show a sleeve fitted in a hole 13

in the binnacle top, the axis of the sleeve being vertical and the interior thereof being of smooth cylindrical form providing a bearing for a quill 14. Adjacent the head of the sleeve is a shoulder 15 which is seated against the upper surface of the binnacle top, and a lock nut 16 threaded upon the lower end of the sleeve coöperates with the under surface of the said top to fix the sleeve rigidly but removably in position. Said head carries a set screw 17 which may be located on any side of the sleeve according to the personal preferences of the navigator prior to the locking effect of the nut 16. The quill or stem 14 as above premised is located rotatably within the sleeve 12 and is provided with a flange 18 adjacent its upper end which rests upon the head of the sleeve. The lower portion of the quill is screw threaded and a collar 19 threaded thereupon is adapted to bear lightly against the lower end of the sleeve to prevent vertical movement of the quill. A set screw 20 operating through this collar is adapted to secure it from accidental movement around the quill. The quill is provided with an interior smooth cylindrical bore 21 into which is adjustably fitted a vertical rod 22. The quill, however, is provided with a lug 23 of any suitable nature extending radially into a groove 24 formed in the rod and extending from the lower end thereof upwardly to any desired distance. The lug prevents rotation of the rod independently of the quill. The upper end of the quill is split as indicated at 25, and exteriorly screw threaded as at 26 for coöperation with a clutch thimble 27 for locking the rod at the desired vertical adjustment within the bore 21. The lower end of the quill 14 is provided with a vertical diametrical slot 28 having parallel sides through which a screw or pivot 29 is adapted to pass perpendicularly to said sides.

At 30 is indicated a pointer of any suitable form or length coöperating with the compass dial but out of contact therewith. The pointer, however, operates radially with respect to the axis of the quill and rod 22. At its upper end the pointer is provided with a disk-shaped hub 31 fitted within the slot 28 and pivoted upon the pivot 29. The pointer, therefore, may be adjusted freely

up and down around the pivot 29 so as to accommodate its point to varying conditions with respect to the compass dial, the pointer, however, being maintained always 5 in the same vertical radial plane with respect to the quill and rod. As a preferred means for determining the elevation of the point of the pointer, I provide a runner 33 threaded upon the extreme lower end of the 10 quill, the same including a cylindrical flange 34, the upper edge of which bears against the pointer shank adjacent the hub 31. Obviously by screwing up the runner said edge will lift the pointer to the desired extent, the extent of adjustment being quite delicate because of the screw action. A set 15 screw 35 acting through the body of the runner against the quill serves to lock the runner at the desired point of adjustment.

20 At the upper end of the rod 22 is formed an open yoke or loop 36 lying in a vertical plane at right angles to the vertical plane of the pointer. The side bars of the yoke are parallel to each other and the opposing 25 faces are flat and smooth, forming bearing surfaces for a cylindrical block 37 pivoted for rotation therein upon a pair of pivot pins or screws 38 extending through the said side bars of the yoke on the same horizontal 30 axis. The screws 38 may be tightened more or less to determine the frictional engagement between the yoke and the block and hence the degree of friction desired for the block tending to resist its pivotal movement 35 in the yoke. The block is provided with a bore 39 extending therethrough with its axis perpendicular to the axis of the screws 38, and in this bore 39 is adjustably fitted the barrel of a sighting tube 40 preferably of 40 cylindrical form. This sighting tube is provided with an eyepiece 41. The sighting tube obviously may be adjusted both rotarily and longitudinally in the bore 39, and when so adjusted may be locked by means of a set 45 screw 42 with which cooperates a jam nut 43 to make the adjustment more secure.

The structure herein set forth in detail is of a comparatively simple nature and hence easily assembled or disassembled. The axis 50 of the sighting tube is arranged in the same vertical plane as the pointer and is maintained therein by reason of the pivotal connections described, irrespective of the vertical movements in said plane. The navigator, therefore, may readily indicate upon 55 the compass dial the location of any distant object or light that he may view through the sighting tube, and such indication may be made permanent, as desired at times, by the 60 action of the set screw 17.

The parts of the device when separated occupy comparatively little space, the structure of the rod 22 being such that it is adapted to nest within the sighting tube.

The instrument is neat in appearance and 65 adds greatly to the efficiency of the steering apparatus.

I claim:

1. In a device of the class set forth, the combination of a vertical rod, means to secure said rod for rotation around its axis in a ship's binnacle, a pointer operated from the lower end of the rod, the upper end of the rod being provided with an integral yoke having parallel side bars with smooth inner 75 surfaces, the yoke lying in a vertical plane at right angles to the plane of the pointer, a bearing block within the yoke, said block having smooth flat ends coöoperating with said smooth inner faces of the yoke bars, means frictionally securing the block in the place indicated for rotation around a horizontal axis, and a sighting tube carried by said block.

2. In a device of the class set forth, the combination of a vertical rotary rod, a pointer carried at the lower end of the rod and extending in a radial direction from the axis of the rod in a certain plane, a yoke formed at the upper end of the rod in a vertical plane at right angles to the aforesaid plane, a pair of pivots extending in the same horizontal axis through the sides of the yoke, a cylindrical bearing block journaled upon said axis within the yoke, the ends of the block being flat and having frictional engagement with the sides of the yoke, said block having a bore therethrough at right angles to the axis of the pivots, a cylindrical sighting tube adjustable rotarily and longitudinally of said block bore, and means acting through the block against the tube to secure it in adjusted position.

3. The combination of a vertical rod, a sighting tube pivoted to the upper end of the rod for movement in a definite vertical plane with respect to the rod, means to support the rod for rotation around its axis, a pointer pivoted adjacent the lower end of the rod and extending radially from the axis thereof in the same plane as the axis of the sighting tube, and means to adjust the pointer vertically around its horizontal pivotal axis, said adjusting means comprising a vertically adjustable rotary member bearing 110 upon the shank of the pointer, substantially as set forth.

4. The combination of a quill having an axial bore and a screw threaded lower end, a rod fitted non-rotarily within the quill 120 bore, a sighting tube connected to the upper end of the rod, means to support the quill and rod for rotation around a fixed vertical axis, the lower end of the quill having a diametrical slot arranged in the same vertical plane as the axis of the sighting tube, a pointer having a disk-like hub journaled on a horizontal axis in said quill slot and ex-

tending thence radially in the aforesaid vertical plane, and a runner threaded upon the lower end of the quill and having a cylindrical flange at its upper end bearing against
5 the lower portion of the pointer adjacent the hub for adjusting the pointer vertically, substantially as set forth.

In testimony whereof I have signed my name to this specification in the presence of two subscribing witnesses.

EDWARD YOUNG HASKELL.
